UNITED STATES PATENT OFFICE.

JULIUS H. HAMPP, OF NEW YORK, N. Y.

MATERIAL-CLAMPING MECHANISM FOR SLICING-MACHINES.

1,091,655.

Specification of Letters Patent. Patented Mar. 31, 1914.

Original application filed April 12, 1910, Serial No. 554,932. Divided and this application filed July 5, 1912. Serial No. 707,691.

To all whom it may concern:

Be it known that I, JULIUS H. HAMPP, citizen of the United States, residing in the city of New York, borough of Bronx, county 5 and State of New York, have invented a certain new and useful Material-Clamping Mechanism for Slicing-Machines, of which the following is a specification.

This invention is a material clamping 10 mechanism for slicing machines, the same being in part a division of a prior application filed by me April 12, 1910, Serial No. 554,932.

The objects of the invention are to se- 15 curely retain the material in a fixed position upon a table regardless of the shape of the mass of such material; to easily and quickly release the retaining means, and to release the locking means and adjust the retaining 20 means by the movement of a single operating device.

The invention embodies a carrying member and a material clamping member pivoted to said carrying member whereby said 25 clamping member is adapted to adjust or accommodate itself to the shape of the material, whereas the carrying member is movable in a direction to shift the clamping member according to the size of the mass of 30 material.

The invention embodies means coöperating with a rack for locking the carrying bar, and a single operating device so re- 35 lated to the carrying bar and to the locking means that by a certain movement of said operating device the locking means is released and movement is imparted to the carrying bar.

In a preferred form, the locking means 40 is a dog pivoted to the carrying bar and held by a spring normally in engagement with the rack bar. The operating member is a piece pivoted to the carrying bar, said member having a stud positioned for en- 45 gagement with the locking dog and pro- 50 vided, also, with a toe piece adapted for engagement with the carrying bar. As stated, the dog is normally in fixed engagement with the rack bar, but when the operating member is operated by hand, then the following movements take place; at the beginning of the operation, the stud acts on the dog to press it against the tension of the spring and out of engagement with the rack 55 bar; then the toe piece bears upon the car-

rying bar, or a part thereof, so as to have a firm bearing thereon, and thereafter the carrying bar with the pivoted clamp is shifted up or down according to the direction of movement of the operating piece, during 60 which movement the dog is held in a repressed position and free from engagement with the rack bar.

Other features of the invention, and the advantages thereof, will appear from the 65 annexed detailed description.

In the accompanying drawings, I have illustrated one practical embodiment of the invention, but the construction shown therein is to be understood as illustrative, only, 70 and not as defining the limits of the invention.

Figure 1 is a side elevation of my ma- 75 terial clamping mechanism applied to a part of a slicing machine. Fig. 2 is a plan view thereof. Fig. 3 is an elevation of a part of the device with the locking member in a released position. Fig. 4 is a transverse section taken on the line 4-4 of Fig. 1. Fig. 5 is a like section taken on the line 80 5-5 of Fig. 1, and Figs. 6 and 7 are detailed perspective views of the operating member and the locking member, respec- 85 tively.

A, designates a table, shown in the ac- 85 companying drawings as a part of a ma- terial slicing machine, said table being pro- 90 vided with a post B positioned on one side thereof so as to extend upwardly. The up- per end of this post is bifurcated, as at b, 90 and within said bifurcated portion is piv- 95 oted one end of a carrying member or bar C by means of a pin c. At the other side of table A, is an upright rack, D, the same being provided on one of its edges with a series of ratchet teeth d. Said rack is curved on an arc, the center of which is co- 100 incident with the pin c.

E, designates an operating member, shown in detail in Fig. 6 of the drawings, said mem- 100 ber being embodied as a lever having one of its ends forked at e. The forked end of said lever is provided with depending ears e', e', whereby said lever is constructed in a man- 105 ner for the forked end thereof to straddle the rack bar D, and be pivotally attached to the bar C by means of the pin c² which passes through said bar and through said depending ears e' of said lever.

The locking member for bar C is shown 110

as a dog F, the same consisting of a yoke f and an arm f'. The yoke f straddles the forked end of the lever, and the ears e' of the operating member are positioned between the yoke and the sides of carrying bar C, said ends of the yoke having apertures f² through which passes the pin c², see Fig. 4, whereby the dog is pivoted to the carrying bar C by the same pin which serves as the pivot for the operating member E. The free end of the arm f' is slotted so as to straddle a post G, the latter extending upwardly from the bar C, and a spring g is coiled around said post between the bar or carrying member C and the arm f' of the locking member, which spring normally exerts tension upon the locking dog and presses the forward edge f³ of said dog into engagement with a tooth of the rack D, thus securely locking the carrying bar C against upward movement.

The operating member E is provided with a stud e³, which is so positioned (see dotted lines in Figs. 1 and 3) as to be in operative relation to the yoke f of the dog F when said dog is in a normal locked position. Said operating member E is provided, also, with a toe piece, e⁴, which toe piece lies between two studs or stops c³, c⁴, positioned on the carrying bar, said studs or stops limiting the up and down movement, respectively, of the toe piece.

On the carrying bar C, intermediate the ends thereof, is a depending hanger lug c⁵, the latter having near its end an aperture c⁶, see Fig. 5. To this hanger lug is loosely connected a material clamping member H, the latter being provided with a forked arm H'. Said forked arm straddles the depending hanger lug c⁵, and is secured thereto by a pin h, passing through the aperture c⁶ in the lug and similar apertures in the forked arm H'.

The gripping member H is provided, preferably, with a roughened under surface, such as the impaling teeth h, shown in Fig. 1, and a similar series of spikes a, may be provided on the table A, the same being adapted to coöperate with the teeth h' for holding the material to be sliced in fixed position.

The operation of the device is as follows:—With the carrying bar in a raised position, the locking member engages with a tooth near the upper end of the rack. The material to be sliced can now be easily inserted beneath the clamping member H and impaled upon the spikes upon the table A. It is only necessary to press downwardly upon member E, bring toe piece e⁴ into contact with stud c³, and this downward pressure impels bar C and clamp H in the same direction, the dog sliding freely over the teeth of the rack. When the carrying bar is shifted downwardly until the roughened

under face of the gripping member engages the upper surface of the material impaled on the spikes a, sufficient pressure is exerted on the carrying bar to force the teeth into said material. This operation of gripping the material is facilitated by having the member H pivoted to the carrying arm, for the reason that said member readily adapts itself to the shape of the material. When the said material has been gripped sufficiently tight to adequately hold it in fixed position while the slicing operation is going on, the pressure on the handle e is relaxed, and the spring g lifts the arm f' and moves the dog into engagement with the rack, thereby locking bar C and clamp H in fixed positions. When it is desired to remove the material, the operator raises the lever E, as indicated by the arrow in Fig. 1. This movement brings the stud e³ into engagement with the forward edge of dog F, and presses said dog rearwardly against the tension of the spring g, whereby the dog is disengaged from the tooth of the rack bar. Now, when the dog has been forced back to secure sufficient clearance between the nose of the dog and the teeth of the rack, the toe piece e⁴ on the operating member engages the stop c⁴, see Fig. 3, thereby securing a firm bearing of the operating member upon the carrying bar, whereby pressure upon the operating member results in shifting the carrying bar in an upward direction.

It will be noted that the dog and operating member coöperate so effectually that but a slight movement of the latter is required to speedily disengage the said dog from the rack, the dog moving in almost a straight path when pressure is applied to disengage the dog.

When the slicing operation is completed, the operating lever E may be pressed upwardly, thus releasing the dog from the rack and allowing the carrying bar to be raised to a position where it will not interfere with the removal of one material from the table A and the installation of other material upon said table.

While I have shown and described the present invention as particularly well adapted for use as a material clamping mechanism for slicing machines, it is evident that the device may be used, either in whole or in part, in other arts.

As heretofore stated, the invention of this application is a division of my prior application Serial No. 554,932, except as to member c⁴ and the bifurcated structure of the dog.

Having thus fully described the invention, what I claim as new, and desire to secure by Letters Patent is:—

1. In a device of the class described, the combination with a carrying member and a rack bar, of pivoted locking means for

- said carrying member, and a pivoted operating device coöperating with the locking means and the carrying member for imparting movement thereto.
- 5 2. In a device of the class described, the combination with a table, of a carrying member and a rack bar, of spring actuated locking dog pivoted to said carrying member, and an operating lever pivoted to the carrying member and coöperating with the locking dog and said carrying member for imparting movement thereto.
- 10 3. In a device of the class described, the combination with a carrying member and a rack bar, of a spring impelled dog mounted on said carrying bar and normally held in engagement with said rack bar, an operating lever mounted on the carrying bar, means on said operating lever for releasing said dog, and a toe piece on said operating lever positioned for engagement with the carrying bar and operating to secure a firm bearing for the operating lever upon said carrying bar.
- 15 4. In a device of the class described, the combination with a carrying member and a rack bar, of a locking dog pivoted to said carrying member for movement therewith, and an operating lever having means for releasing the locking dog and to impart movement to the carrying member, said operating lever being effective in retaining the locking means in a disengaged position while moving the carrying member.
- 20 5. In a device of the class described, the combination with a carrying member and a rack bar, of a locking dog mounted on the carrying member for engagement with the rack bar, and an operating member separate from the locking dog, said operating member being movable successively to positions for releasing said locking dog and for imparting movement to the carrying member.
- 25 6. In a device of the class described the combination with a carrying member and a rack bar, of a locking dog on the carrying member, and an operating member coöperating with the locking dog and pivoted to the carrying member for imparting movement to the dog and the carrying member successively, said dog and operating member being so related to each other as to effect the disengagement of the dog from the rack bar at the initial movement of said operating member.
- 30 7. In a device of the class described, the combination with a carrying member and a rack bar, of a locking dog mounted on the carrying member for engagement with the rack bar, and a separate operating lever pivoted to the carrying member and having means coöperating with said locking dog, said operating lever being movable for releasing said dog and for subsequently imparting movement to the carrying member.
- 35 8. In a device of the class described the combination with a carrying member and a rack bar, of a locking yoke shaped dog pivoted near one end to said carrying member and having a rearwardly extending arm, a spring for retaining said arm in a raised position, whereby the forward edge of the dog normally engages the rack, and an operating member mounted on said carrying member positioned to release said locking member.
- 40 9. In a device of the class described the combination with a carrying member and a rack bar, of a locking member mounted on said carrying member and positioned to engage with the rack bar, and an operating lever mounted on the carrying bar, said lever having a bifurcated end adapted to straddle the rack bar and pivoted to the carrying member and means on said bifurcated portion of the lever positioned for engagement with said locking member for disengaging the latter from the rack bar.
- 45 In testimony whereof I have signed my name to this specification in the presence of two subscribing witnesses.
